Cabot Electric Company, Roxbury, Mass., a cor-
poration of Massachusetts

Application January 4, 1928. Serial No. 244,534

1 Claim. (Cl. 177—329)

The present invention relates to an improvement in annunciators.

The objects of the invention are to produce an annunciator of high legibility and certainty of action, inexpensive in construction, and of durability. To the above ends the present invention consists in the construction hereinafter described and particularly defined in the claim.

In the accompanying drawing illustrating the preferred form of the invention, Fig. 1 is a perspective view of an annunciator box particularly intended for use in connection with elevators, embodying the invention; Fig. 2 is a perspective view of the glass plate in the front of the box; Fig. 3 is a sectional plan taken on the plane 3—3, Fig. 1; Fig. 4 is a diagrammatic view illustrating the glass front and the floor indicators, of which one is in position against the glass showing on one side of the view the front of the glass with the floor-indicating figure legible; Fig. 5 is a similar view with no floor-designating indicator operated, showing the appearance of the glass on the left when no floor is designated; Fig. 6 is an enlarged view of the indicator and the hood which embraces the indicator disk; and Fig. 7 is a view of an indicator taken at right angles approximately to the view shown in Fig. 6.

The illustrated embodiment of the invention is described as follows: The box 10 is a metal casting having an opening 11 in its front. This opening is closed by a glass plate 12, which has two columns of figures upon it indicating the floor numbers. This glass plate is secured inside of the opening 11 in a manner presently to be described. This glass plate is a photographic negative, the film side being on the rear and the plain glass side on the front. The film is opaque and black except where letters and figures appear thereon. At those places it is transparent. The back of the film is painted white behind the words "Up" and "Down", so that these words are always legible. The figures indicating the floors are not normally legible because the inside of the box is dark. When, however, a white target is pressed against the film behind one of these transparent figure areas, the white target renders the figure legible. As shown in Fig. 6, when no target is in contact with the glass, the figures are invisible, but when a target, as the target for the figure "4" is pressed against the glass, its white face shows through the transparent figure opening, and, as shown in Fig. 4, the floor number "4" becomes visible.

The targets, consisting of disks 13, are covered with a layer 14 of white plush or velvet glued

thereon. Obviously, when this target is pressed against the transparent portion of the glass, the figure becomes visible. Each target is provided with a rod 15, by which the target is supported. The target rod consists of two parts, an aluminum portion 16, and a soft iron portion 17. The aluminum portion 16 is provided with a dowel 18, which is received with a drive fit in a hole bored in the end of the iron portion 17 of the target rod 15. The front end 19 of the aluminum portion 16 of the target rod is reduced in size and is received in a hole in the arm 20, which arm is forced on to the reduced end 19. The extreme front end of the reduced portion 19 penetrates the target disk 13, and is riveted therein at 22. The covering of the face of the target is preferably white by reason of its light reflecting excellence, but other contrasting colors may be used to render the character areas legible.

The extreme end of the target arm 20 is round and received in a slot 24 in the hood or shroud 25. The position of the hood is such that the slot 24 is on one side, as the annunciator is ordinarily supported, and it acts to hold the target either in retracted or advanced position. When the target is retracted, it occupies the position shown in Fig. 6; when the target is advanced it occupies the position at the other end of the slot with the face of the target in contact with the glass. This curved slot, therefore, operates normally to hold the target, owing to its two inclined ends, either in its advanced or retracted position. The open face of the hood is pressed against the glass, and it prevents light from obtaining access to the rear of the glass plate except to the extent to which light may enter through the figure openings in the film.

Each target rod is supported in a double coil solenoid 26, the rear coil 27 when energized acting to pull the target into its retracted position, and the front coil 28 when energized acting to move the target to its advanced position. These solenoids are mounted on the plate 29, and as many solenoids are employed as there are floor numbers provided in the glass. On the front of the plate are supported the hoods 25, one hood being provided for each target. The glass 12 is placed in position in a recess provided for it in the back of the front plate 30 of the box. Against this glass, and holding it in position, the hoods of the several annunciator solenoids press, the plate 29 which carries the solenoids and hoods being supported upon four long screws 31 screwed into screw-threaded holes in the back of the front plate 30 of the box, and be-

ing provided with springs 32 which are interposed between the heads of the screws 31 and the plate 29, so that the hoods are pressed with yielding pressure against the glass plate of the 5 box.

It will be understood that the appearance of the box as illustrated in Fig. 1, does not correspond to its appearance as viewed by the eye, as the glass, with the exception of the words 10 "Up" and "Down" which will appear white, will be black, or substantially black in appearance, and the several figures will be wholly invisible to an ordinary examination. When, however, any solenoid is energized to advance a 15 target, it will press the white face of the target against the film side of the glass, and the light entering through the figure opening will illuminate so much of the white face of the target as is exposed through the figure opening 20 in the film, and thereby the portion of the target exposed through the figure opening will be visible, and white figures indicating the floors will exhibit themselves. So the normal appearance of the glass front plate of 25 the box will be black, except for the words "Up" and "Down" which will be permanently white, and the floor figures will appear in white when the solenoid advances the floor target into contact with the film. So, in Figs. 4 and 5 the 30 left hand side of the figure, which shows a partial front elevation of the glass plate, will be shown in white instead of black in Fig. 4, on the left hand side where the face of the glass is shown.

35 It is possible, but difficultly possible, by seeking a particular position of the eye for viewing the front plate of the box from which the floor figures in the plate may be dimly visible, even when all of the targets are in retracted position, but none of them will appear white, and great difficulty will be experienced in obtaining 40 a position from which to be able to see such figures, the fact being that a photographic plate, viewed from the glass side against a dark background, shows the image on the film with great 45 difficulty and then only dimly, so that this front plate is excellently well adapted by ordinary observation to exhibit a solid black face except when the targets are pressed against the glass, 50 so that illumination may flow through the glass to the target and thus enable the eye of the observer to see the figure.

When the target, however, is in contact with the glass, the illumination from outside renders 55 the figures clearly and distinctly legible. The illegibility of the figures under ordinary circumstances, with the targets retracted, is accentuated by the target hoods, which prevent almost all light from access to the target when it is in 60 retracted position, except such as enters through the figure opening at the front, but the amount of such light entering the hood from the figure opening in the front plate is insufficient to illuminate the target in retracted position, so that it 65 will be visible to the eye of the observer.

A transparent glass front over a series of targets each bearing numerals would permit the

illumination of all target-bearing numbers such that it would be difficult to distinguish between the targets which were pressed against the glass and those which were in retracted position. One feature of the invention, therefore, consists in forming the front plate of opaque material with character-shaped areas or openings therein or thereon acting to illuminate the target or render the characters legible when in indicating position in contact with the back of the plate. The characters may be on the plate or the targets.

80 The front plate of the annunciator is very conveniently manufactured by making a drawing of the front plate in black and white of the size desired. From this drawing a photographic negative will be made exactly of the same size as the desired front plate of the box. A positive is made from the negative by contact printing which, in turn, is used as the means of making as many further identical negatives as may be 85 required. These negatives form the finished front plates for the box.

The electrical connections between the solenoids and the push buttons of the several floors and the restoring button on the car, may all be 90 as is usual for the usual form of annunciator for use in elevators.

The invention may also be used, of course, for making annunciators for general uses, or for special uses. Words may be substituted for floor 95 figures upon the front plate without any change being required in the targets or the remainder of the box mechanism.

A feature of the invention consists in the photographic front plate for an annunciator box 110 having normally invisible indicating openings adapted to be rendered visible by the application of a white or light colored material to the back of the plate by any suitable mechanism.

Other forms of plate are within the scope of 115 the invention, viewed in its broader aspects. A transparent cover of glass or other material may be used in addition, if desired. Generically considered, the invention contemplates the use of a plate having an opaque body, and a rear member, one of such members being provided with a contrasting character area, the arrangement being such that the character is legible when the members are close together and illegible when separated. It also contemplates an opaque plate 120 with indicating openings therethrough of less opacity, used in connection with means for applying light reflecting material to the back of the plate to cause visibility of the selected indication.

130 Having thus described the invention, what is claimed is:

An annunciator comprising a solenoid, a target adapted to be moved axially by the solenoid, a lateral projection on the target, and a guide member at the side of the target, the guide member being provided with a slot to receive the projection, the slot comprising two portions downwardly inclined toward its ends to hold the target in either its retracted or its advanced position. 140
